UNITED STATES PATENT OFFICE.

JOHN THOMAS CRENSHAW, OF DERMOTT, ARKANSAS.

MEASURING DEVICE.

No. 830,211.

Specification of Letters Patent.

Patented Sept. 4, 1906.

Application filed November 1, 1905. Serial No. 285,431.

To all whom it may concern:

Be it known that I, JOHN THOMAS CRENSHAW, a citizen of the United States, residing at Dermott, in the county of Chicot and State of Arkansas, have invented a new and useful Improvement in Measuring Devices, of which the following is a specification.

My invention relates to certain new and useful improvements in measures for all kinds of goods wound or rolled upon a board or core, and has for its object to provide a simple and cheap device that can be easily and quickly attached to the board or core and one that the number of yards left in the bolt can be told at a glance, which will be a great time-saver when taking stock.

A further object of my invention is to provide a device that will be out of the way when attached and one that is provided with a spring-tongue which engages the tape and prevents it from unwinding too freely.

With these objects in view my invention consists of the novel construction and arrangement of parts hereinafter described, pointed out in the claims, and shown in the accompanying drawings, in which—

Figure 1 is a perspective view of a bolt of goods with the device attached. Fig. 2 is a perspective view of the device attached to a board. Fig. 3 is a longitudinal section through the device and board.

Referring to the drawings, A indicates the board upon which the cloth B is wound and to which I secure my device adjacent one end. The device consists of a casing C, the sides C' of which are provided with perforated flanges C², by means of which it is adapted to be secured to the boards by screws or tacks. The top of the casing at its inner end is provided with an outwardly-projecting member C³, which is bent downwardly and inwardly and then back upon itself, by means of which the end of the graduated tape D, which may be of paper or cloth, is secured in the casing. The tape is folded in the casing, and the free end projects out between the spring-tongue C⁴ of the casing and the board, which prevents the tape from unwinding too fast by the functional surface of the tongue.

In use the tape indicating the number of yards and placed in the casing will correspond to the number of yards of cloth in the bolt, and after the required amount of cloth has been unwound the tape is drawn out and laid along the edge of the cloth, and the desired amount of cloth is cut off, and with it the tape, and the remaining tape will show the number of yards of goods left in the bolt.

Having thus fully described my invention, what I claim as new, and desire to secure by Letters Patent, is—

1. In a device of the kind described the combination with a board or core upon which a bolt of goods is adapted to be wound, of a casing secured to the board adjacent one end, a tape secured in said casing by a member of the casing, and a spring-tongue forming a part of the casing adapted to engage the tape as it passes out of the casing, for the purpose described.

2. In a device of the kind described the combination with a board or core upon which a bolt of goods is adapted to be wound, of a casing secured adjacent one end carrying a tape indicating the whole number of yards of cloth in the bolt of goods, one end of the tape being secured in the folds of the downwardly-projecting member of the casing, and a spring-tongue forming the other end of the casing adapted to engage the tape as it passes out for the purpose described.

3. In a device of the kind described, the combination with a core upon which a bolt of goods is adapted to be wound, of a flanged casing secured on one side of the core adjacent one end, a tape indicating the number of yards on the bolt, arranged in said casing, one end of said tape being secured in the folds of the downwardly-projecting member of the casing, and a spring-tongue adapted to engage the tape as it passes out, for the purpose described.

JOHN THOMAS CRENSHAW.
